UNITED STATES PATENT OFFICE

100,022

DESIGN FOR A BURIAL VAULT HANDLE

Roe P. Henderson, Springfield, Ohio, assignor to
The Springfield Metallic Casket Company,
Springfield, Ohio, a corporation of Ohio

Application April 24, 1936, Serial No. 62,281

Term of patent 7 years

To all whom it may concern:

Be it known that I, Roe P. Henderson, a citizen of the United States, residing at Springfield, in the county of Clark and State of Ohio, have invented a new, original, and ornamental Design for a Burial Vault Handle, of which the following is a specification, reference being had to the accompanying drawing, forming part thereof.

The figure is a perspective view of a burial vault handle, showing my new design.

I claim:

The ornamental design for a burial vault handle, as shown.

ROE P. HENDERSON.
